L. HORRALL

STATIONERY CONTAINER

Filed Oct. 19, 1923

Logan Horrall, Inventor

By H. Woodward Attorney

Patented Apr. 20, 1926.

Des. 69,945

UNITED STATES PATENT OFFICE.

LOGAN HORRALL, OF INDIANAPOLIS, INDIANA.

DESIGN FOR A STATIONERY CONTAINER.

Application filed October 19, 1923. Serial No. 7,549. Term of patent 3½ years.

To all whom it may concern:

Be it known that I, LOGAN HORRALL, a citizen of the United States, residing at Indianapolis, in the county of Marion, in the State of Indiana, have invented a new, original, and ornamental Design for Stationery Container, of which the following is a specification, reference being had to the accompanying drawings, forming part thereof.

The figure is a perspective view of the container illustrating my new design.

I claim:

The ornamental design for a stationery container, as shown.

LOGAN HORRALL.
